UNITED STATES PATENT OFFICE.

ARNE KRISTIAN HILBERG BJORGE, OF ST. PAUL, MINNESOTA.

ELECTRIC THIRD RAIL.

1,388,088.

Specification of Letters Patent. Patented Aug. 16, 1921.

Application filed December 17, 1919. Serial No. 345,668.

To all whom it may concern:

Be it known that I, ARNE KRISTIAN HILBERG BJORGE, a citizen of Norway, residing at St. Paul, in the county of Ramsey and 5 State of Minnesota, have invented certain new and useful Improvements in Electric Third Rails, of which the following is a specification.

This invention relates to improvements in 10 electric feed conductors or third rails for electric railways and the invention has for its object to provide a third rail structure affording a maximum degree of safety and protection produced by local energization 15 of successive sections of the rail during travel of the car.

Another object is the provision of a third rail of the inverted type which is supported for vertical movement, being automatically 20 elevated by the car carried contact shoe and, when so elevated, being engaged by a feed conductor concealed within the housing or guard for the rail, the latter being constructed of such flexible material as 25 will permit the desired vertical movement thereof.

Another object is the provision of a third rail of this type which is normally retained in its lower or inoperative position by its 30 own weight.

With these and other objects in view as will appear as the description proceeds the invention comprises the novel features of construction, combination and arrangement 35 of parts which will be more fully described in the following specification and then finally pointed out in the claims hereunto appended.

Figure 1 represents a side elevation of the 40 improved third rail, a portion of the guard or housing being removed.

Fig. 2 represents a transverse sectional view on the line 2—2 of Fig. 1, and

Fig. 3 represents a transverse sectional view on the line 3—3 of Fig. 1.

45 Referring to the drawing in detail, wherein similar reference numerals designate corresponding parts throughout the several views, the numerals 5 indicate the opposed side members of the rail housing or guard 50 which are arranged in spaced parallel relation and are connected by the cover strip 6. As usual, the guard is constructed of wood or other nonconducting material and according to the present invention is provided with a 55 plurality of uniformly spaced supporting members 7 secured between the side walls 5 of

the guard midway the top and bottom edges thereof. Insulators 8 are arranged in the guard 5 intermediate and above the supports 7 and receive and support the horizontally 60 extending feed conductor 9 which is supplied with current from the source of supply.

The third rail 10 which, as usual, is constructed of conducting material is arranged underneath the guard 5 and is movable upwardly therein incident to contact of the contact shoe of the railway car therewith. A supporting strip 11 is secured at intervals by rivets or suitable fastening devices 12 to the rail 10 and the material of the strip lying 70 intermediate the fastening members 12 is bent upwardly to provide substantially inverted U-shaped supporting members 13 positioned over and supported by the members 7 of the guard. In its normal position, the 75 rail 10 is disposed slightly below the lower edges of the guard 5, the web portions of the U-shaped members 13 resting upon the supporting members 7 so that when the rail is engaged and elevated by contact with the 80 shoe of the car, enough of the rail is exposed to form an electrical connection with the car shoe. Incident to the vertical movement of the rail the web portions of the U-shaped members 13 are brought into contact with 85 the conductor 9 forming an electrical connection therewith and supplying current to the rail 10. To insure an efficient electrical connection between the U-shaped members 13 and the conductor 9 the web portions of said 90 members 13 are preferably curved transversely so as to conform with the contour of the conductor 9 and, as will be understood, the rail 10 possesses a sufficient degree of resiliency to permit flexure thereof such as 95 necessarily is incident to the elevation of each set of strips 11 successively by contact with the contact shoe of the car therewith.

The rail 10 is formed in a plurality of sections and although comparatively short 100 lengths of the rail sections are shown in the drawing, it will be understood that the latter may be of desired length and the several sections are insulated from each other by the insulating blocks 14 constructed of 105 wood or other nonconducting material provided with opposed reinforcing plates 15. The terminals of the adjacent rail sections are disposed in spaced relation and receive a depending extension 16 carried by the insulator 14 whereby the passage of the current from one rail to another is prevented 110

and only one rail in the third rail track is energized at a time.

At road crossings or other third rail terminals, a relatively thin rail strip 17 is rigidly secured to the extremity of the main rail 10 and is provided with a curved terminal 18 secured under the cover strip 6, the exposed portion of the rail section 17 being disposed at an inclination to gradually contact with the shoe of the car as the latter approaches or moves away from the rail, the rail section 17 being constructed of spring metal, as will be understood, so as to afford the requisite degree of resiliency. 10 The adjacent wall portion of the guard 5 is preferably to be lined with metal, (not shown) to eliminate possibility of fire resulting from sparks produced by the making and breaking of the electric circuit, between 15 the contact faces of the strip 11 and the opposed faces of the rail 9.

What I claim is:

1. A device of the character described comprising a guard including spaced insulators, 25 a feed conductor supported in the insulators and extending between the latter, a flexible conducting rail adapted to be elevated by engagement with the contact shoe of a railway car, spaced contact members carried by 30 the rail adapted to engage and electrically connect with the feed conductor and normally maintained in inoperative position by its own weight, and guard carried means arranged to normally support the contact members in position below the feed conductor. 35

2. A device of the character described, comprising a guard housing formed of an insulated material, a conductor strip within

said guard housing and co-extensive therewith, and having portions of the same exposed in recesses spaced along one face of said guard housing, flexible rail sections disposed in end to end relation one insulated from the other and extending along the recessed face of said guard housing, and contact strips carried by said rail sections and projecting into said recesses, and adapted to be forced into contact with the complementary exposed face portion of said conductor strip, when said rail sections are flexed by the contact shoe of a passing car, whereby one rail section is energized at a time. 40 45 50

3. A device of the character described comprising a guard housing formed from an insulated material and having spaced recesses opening through the under face thereof, a conductor strip within said guard housing and having portions thereof exposed in the recesses of the latter, flexible rail sections disposed along the under face of said guard housing in end to end relation one insulated from the other, insulating members extending across said recesses and inwardly thereof, and contact strips looped about said insulating members and each having their opposite ends secured to the inner faces of said rail sections, said contact strips being adapted to be forced into contact with the complementary portions of said conductor strips, when said rail sections are flexed by 60 65 70 the contact shoe of passing cars, whereby one rail section is energized at a time.

In testimony whereof I affix my signature hereto.

ARNE KRISTIAN HILBERG BJORGE.
